UNITED STATES PATENT OFFICE.

RICHARD H. HATFIELD, OF BROOKLYN, NEW YORK.

MEANS FOR SYNCHRONIZING AND HARMONIZING MOVING-PICTURE EXHIBITIONS.

1,352,126.

Specification of Letters Patent.

Patented Sept. 7, 1920.

Application filed September 26, 1919. Serial No. 326,582.

To all whom it may concern:
Be it known that I, RICHARD H. HATFIELD, a citizen of the United States, and a resident of the city of New York, borough 5 of Brooklyn, in the county of Kings and State of New York, have invented certain new and useful Improvements in Means for Synchronizing and Harmonizing Moving-Picture Exhibitions, of which the following 10 is a full, clear, and exact description.

Among the principal objects which the present invention has in view are: to multiply the performances exhibiting photographic productions and musical and other 15 sound effects associated with the same; to synchronize the operation of moving picture projecting machines in correspondence with a master machine; to continuously advise an operator at a branch station of the relation 20 of the machine being operated by him with that of the machine at the master station; and to provide systems of indicators adapted for comparison.

Drawings.

Figure 1 is a schematic view of a master exhibit and auxiliary exhibits electrically connected therewith.

Fig. 2 is a detail view showing a fragment 30 of photographic film used in projecting machines employed for producing moving pictures.

Fig. 3 is a detail view indicating a diagram of the projecting machines employed 35 in the master exhibit.

Description.

The present invention has in view to connect a main or master exhibition with auxiliary or minor exhibitions by means of electric communication, so that the operator of the projecting machine at the auxiliary exhibition is kept momentarily advised of the operation condition of the projecting machine 40 of the main exhibition, so that he may control the projecting machine in his branch or minor exhibition in harmony or time with the musical composition produced in the master exhibition and communicated to the 45 branch exhibition telephonically.

With this end in view the master exhibition A is furnished with a sound collecting device or megaphone 8, which is provided with telephonic transmitting means for communicating effects over the wires 9 to receiver megaphones 10 having telephonic re-

ceiving instruments attached thereto. The megaphones 10 are multiplied and distributed in the branch or minor exhibitions B, of which there are two shown in the drawings. The megaphone 8 is disposed in advantageous juxtaposed relation to the orchestra pit 11 in the exhibit A, so that the musical sounds produced by the orchestra in the pit are simultaneously heard in the master exhibit A and in the branch exhibits B.

The music of the orchestra in the main exhibit A is usually complementary to the photographic reproduction being thrown on the screen 12 by the projecting machines 13, of which there are usually two. Each of the machines 13 is driven by electric motors 14, current for which is supplied from electric mains when the switch 15 is closed. The purpose in using two machines 16 in exhibitions of the character mentioned is to avoid the delays incident to the adjustment of succeeding reels. Both machines are operatively connected with and drive rotary timers 16. The timers 16 are electrically connected by distributing circuits 17 with odometers 18 situated in the branch exhibits B in view of the operator of the projecting machines 19 in the branch exhibits.

The knife switch 20 in the master exhibit is employed when the operator transfers the use of the projecting machine from one machine to the other. It is evident that the timers 16 on each of the projecting machines in turn operate upon the odometers 18 in the branch exhibits, with the result that in the branch exhibits the odometers 18 continue to progressively add to the numbers.

A timer 21 is electrically connected in each of the branch exhibits with the odometers 22. The odometer 22 is paralleled to the odometer 18 in each of the branch exhibits so that any discrepancy arising 95 between the two odometers is quickly and certainly perceived. As the operator is called upon to maintain the uniformity of the two odometers in order that synchronization 100 of the two machines in the main exhibit and at the branch exhibits may be maintained, the motors 23 at the branch exhibits are furnished with current by a circuit embodying a rheostatic device having resistance segments 24, which may be cut in 110 or out as the case may be, to accelerate or diminish the speed of the motors 23 for

securing synchronization of the picture productions.

To further insure the synchronization of the picture productions the films as shown in Fig. 2 are provided with progressive additive series of numbers imprinted on the margins of the films, so as to be viewed by the operator through a spotlight in the side of the film reel or projector head.

10 Usually the speed of the projecting machine is sixteen photographic reproductions to the second. The numbers are imprinted on the film in series of sixteen each, or sixteen numbers of one volume are imprinted 15 which means that in the spotlight for the view of the operator sixteen numbers of the same power will be shown so that he can see the successive numbers as they pass. These numbers in the picture correspond 20 with the numbers on the odometers 18 and 22 (by comparison with 18 and actually with 22). This marking of the film is particularly advantageous in permitting the operators at the branch stations to splice 25 or repair their films and adjust the film with reference to the odometers mentioned to secure uniformity therewith.

To avoid the disastrous effect of the breaking of a film in the master production 30 A for destroying the continuous run of the odometers 18 to keep up with the branch exhibits the projectors 13 as shown in Fig. 3 of the drawings, use two or duplicated films 25. When using the duplicated films 35 it will be understood the films are run simultaneously and preferably by the same intermittent mechanism or intermittent mechanisms having unit control. The eliminating member 26 with the condenser 40 27 provided therefor are both mounted on a carriage 28, so that they may be shifted from the position shown in full lines of Fig. 3 of the drawings to the position shown in broken lines of said Fig. 3, with 45 the effect that the light traveling through the films 25 is moved from the one film to the other film, and this without loss of time. Time is thus afforded to the operator in which to splice or make other re- 50 pair to the ribbon which has broken. In this manner the operation of the odometers 18 at the branch exhibits B is maintained constant.

From the foregoing it will be understood 55 that an exhibit including photographic and musical reproductions may be carried on at a master exhibit and reproduced simultaneously or synchronously in a number of branch exhibits, the music being transmitted telephonically. From this it is evident that a high class musical performance 60 may be secured at relatively low cost, to be distributed and shared by an increased audience with considerably less, if any, 65 added expense. By synchronizing the per-

formances the added pleasure of the dual effect of music selected with reference to the optical production may be secured and dispensed to audiences which otherwise could not be thus provided because of the 70 relatively high cost of production thereof.

While the present disclosure is shown in the drawings as employing the odometers 18 and 22, it is obvious that other means of registration between the machines at the 75 master exhibit and the machines at the branch exhibits may be employed. One substitution is evident in the drawings where by having the odometers 18 only at the branch station these could be compared with 80 the numerals on the margin of the film 25 to secure similar results. Therefore the invention in its broader sense is not confined to the instrumentalities employed for carrying it into effect for the reason that the instrumentalities so employed may be substituted by a number of well known devices 85 for securing similar results.

Claims.

1. Means for synchronizing and harmonizing moving picture exhibitions comprising, 90 a master stereopticon projecting machine; a plurality of branch projection machines located at distances from said master machine; a plurality of electro-mechanically actuated devices for indicating, visibly, at the operating station of said branch machines, the movement of said master machine; means operatively connecting said 95 devices, said means embodying an electrical supply and distributing circuits connecting said devices for operating the same in unison, and means for varying the speed of said 100 branch machines.

2. Means for synchronizing and harmonizing moving picture exhibitions comprising, 105 the combination of a master exhibition embodying means for producing visible performances, and audible performances, complementary to said visible performances; a plurality of branch exhibitions adapted for producing similar visible performances; and telephonic apparatus communicating between said exhibitions for reproducing, telephonically in said branch exhibitions, audible 110 performances of said master exhibitions. 115

3. Means for synchronizing and harmonizing moving picture exhibitions comprising, 120 the combination of a master exhibition embodying means for producing visible performances, and audible performances, complementary to said visible performances; a plurality of branch exhibitions adapted for producing similar visible performances; telephonic apparatus communicating between 125 said exhibitions for reproducing, telephonically in said branch exhibitions, audible performances of said master exhibitions; and means communicating between said exhibi- 130

tions for indicating the relation of said performances.

4. Means for synchronizing and harmonizing moving picture exhibitions comprising, the combination of a master exhibition embodying means for producing visible performances, and audible performances, complementary to said visible performances; a plurality of branch exhibitions adapted for 10 producing similar visible performances; telephonic apparatus communicating between said exhibitions for reproducing, telephonically in said branch exhibitions, audible performances of said master exhibitions; 15 and means operatively connecting said master and branch exhibitions for indicating the relation of the visible performances at said exhibitions.

5. Means for synchronizing and harmonizing moving picture exhibitions comprising, the combination of a master exhibition embodying means for producing visible performances, and audible performances, complementary to said visible performances; a 20 plurality of branch exhibitions adapted for producing similar visible performances; telephonic apparatus communicating between said exhibitions for reproducing, telephonically in said branch exhibitions, audible performances of said master exhibitions; 25 means operatively connecting said master and branch exhibitions for indicating the relation of the visible performances at said exhibitions; and means located at each of said 30 branch exhibitions for varying the rate of speed of the performances there produced.

6. Means for synchronizing and harmonizing moving picture exhibitions comprising,

the combination of a master exhibition embodying means for producing visible performances, and audible performances, complementary to said visible performances; a plurality of branch exhibitions adapted for producing similar visible performances; telephonic apparatus communicating between said exhibitions for reproducing, telephonically in said branch exhibitions, audible performances of said master exhibitions; and means operatively connecting said master and branch exhibitions for indicating the 40 relation of the visible performances at said exhibitions, said means embodying mechanical indicators for showing the progression of said master exhibition at the operating stations of the branch exhibitions. 55

7. Means for synchronizing and harmonizing moving picture exhibitions comprising, the combination of a master exhibition embodying means for producing visible performances, and audible performances, complementary to said visible performances; a plurality of branch exhibitions adapted for producing similar visible performances; telephonic apparatus communicating between said exhibitions for reproducing, telephonically in said branch exhibitions, audible performances of said master exhibitions; and means operatively connecting said master and branch exhibitions for indicating the 60 relation of the visible performances at said exhibitions, said means embodying a mechanical counter, located adjacent, to the operating stations of branch exhibitions and operatively connected with operating station of 65 said master exhibition. 70

RICHARD H. HATFIELD.
